UNCOUPLING DEVICE FOR TOY RAILROAD CARS

Earl W. Harding, 220 N. Montebello Blvd.,
Montebello, Calif. 90640

Filed Apr. 19, 1971, Ser. No. 135,528

Term of patent 14 years

Int. Cl. D21—01

U.S. Cl. D34—15

FIG. 1 is a perspective view of an uncoupling device for toy railroad cars, showing my new design;

FIG. 2 is a side elevational view, both sides being the same;

FIG. 3 is an elevational edge view taken at right angles relative to the view of FIG. 2, both edges being the same;

FIG. 4 is a top plan view thereof; and

FIG. 5 is a bottom elevational view.

I claim:

The ornamental design for an uncoupling device for toy railroad cars, as shown and described.
